FIG. 8 a rear perspective view of the wearable display device.

D14/432-439, 447, 458, 474, 480.1, 483,

Broken lines are environmental only and form no part of the

D14/484.1, 217, 239, 299; D8/349, 354,

claimed design;

D8/395; D16/100, 330, 300, 309; 345/7-9;

Dash-dot lines adjacent un-shaded areas represent bounds of

351/158; 359/633, 630

the claimed design and form no part of the claimed design

themselves.

The pairs of closely adjacent, spaced jagged broken lines in

the drawings form no part of the claimed design and the

portions between such pairs of jagged broken lines are broken

away to disclose indeterminate length. Portions of the design

that may be visible between the jagged lines have been

removed for clarity.
